UNITED STATES PATENT OFFICE

2,196,924

VENTILATED SHOETREE

Paul S. Jones, Brockton, Mass., assignor to
 Jones & Vining, Inc., Brockton, Mass., a corporation of Massachusetts

Application September 22, 1939, Serial No. 296,125

2 Claims. (Cl. 12—128.2)

My present invention is a novel and improved ventilated shoetree and is directed to improve and perfect this type of shoetree illustrated in my prior Patent No. 2,169,151, dated August 8, 5 1939.

In the manufacture of shoetrees, particularly ventilated shoetrees of the type of my said patent, it has been heretofore customary to form 10 openings, slots, or the like thru the wood of the forepart but only from the rear face of the forepart or from the bottom surface, or from both.

While these prior methods, and particularly such ventilated shoetree structures as that of my said patent, as well also as that of my prior 15 Patent 2,155,015, dated April 18, 1939, constitute important improvements in the art of ventilated shoetrees, they have all been limited to the ventilating features from the bottom or rear face.

With my present invention I have devised a 20 ventilated shoetree structure which provides a ventilating feature from the extreme toe portion rearwardly, which is a distinct novelty, as far as I am advised, in this particular art.

I further provide an automatic self-adjusting 25 and resilient feature in my present ventilated shoe structure, which automatic adjustment extends to the extreme toe portion, and which also is a distinct novelty in this art.

Referring to the drawing illustrating a preferred embodiment of the present invention,

Fig. 1 is a plan view of my improved toe-ventilated automatic self-adjusting shoetree;

Fig. 2 is a side view;

Fig. 3 is a view of the rear face of the shoetree.

As shown in the drawing, a wooden forepart 1 of any suitable design, style, or size of the shoetree is made, which forepart is provided with a series of longitudinal slots, certain of which slots extend inwardly from the toe part 2 and other slots extend inwardly from the rear face 3, while still additional slots may be, and preferably are, provided with openings from the bottom 4. I may and preferably will combine some of the lengthwise slots both from rear and toe portions, together with certain of the slots opening from the bottom, as will be further explained.

Also, I prefer to form the saw-cuts or slots from the rear face 3 forwardly, and from the toe portion 2 rearwardly in spaced or staggered relation to each other and overlapping somewhat, thus providing a yielding and self-adjusting feature for the extent permitted by the width of the slots in the forepart.

After the forepart 1 has been turned in desired 55 form, size, and contour, a plurality of ventilating

slots 4 and 5 are cut or sawed into the wood of the shoetree from the rear face 3 and extending clear thru from the bottom 4 to the top of the last, as shown in Fig. 3. These slots extend a substantial distance forwardly, as indicated in Fig. 1. Thereupon additional saw-cuts or slots 7 and 8 are formed in the forepart from the toe rearwardly in staggered relation to the slots 4 and 5 and overlapping the same, as clearly shown in Figs. 1 and 2.

Thus a considerable yield or self-adjusting feature is afforded because of the overlapping and staggered saw-cut structure, as just described, all of the slots 4, 5, 7 and 8 extending entirely thru the wood of the shoetree from the bottom to the top and, hence, affording extent of widthwise adjustment illustrated by the dotted lines 10—10 and 12—12, which indicate approximately the extent to which either the toe portion or the rear portion of the shoetree may be 20 squeezed to afford the self-fitting feature when it is forced into the shoe.

In addition to the overlapping slots from the toe inwardly and from the rear forwardly, I prefer also to form additional ventilating slots 14 25 and 15 opening from the bottom 4 and extending lengthwise into registry with the toe slots 7 and 8 respectively.

This allows a ventilating circulation of air from the extreme toe portion permitted by slots 30 7 and 8 to emerge at the rear face 3 of the forepart and thus afford a ventilating feature throughout the entire shoetree from the extreme toe portion to the rear face.

Any desired type of toggle mechanism may be 35 connected with the ventilated forepart structure and, as herein shown, I have fitted a threaded member 20 to be threaded into the shoetree 1 and affording a lengthening and shortening adjusting feature by the tightening in or loosening up 40 of this threaded part, as may be readily appreciated and as explained in my said prior Patent No. 2,169,151.

To the member 20 is pivoted at 21 a double 45 toggle lever having arms 22 and 23 carrying a heel-engaging part 25 mounted on the other toggle member 24 pivoted at 26 to the arms 22 and 23, and with a finger-operating and locking handle 30, formed at the opposite end of the toggle member 24 and, preferably, round and therefore of greater width than the opening between the toggle members 22 and 23, thus giving a convenient finger-hold, and also means to bear against the double toggle 22 and 23 and hold the 50 55

same in locked and extended position, as will be readily understood.

I believe that my invention of a shoetree with ventilated toe portion, permitting air circulation from the extreme toe part rearwardly, and also the self-adjusting feature provided throughout, as well also as the staggering of the toe slots, together with rear opening slots and bottom opening slots, giving a self-adjusting capacity both for the toe part and rear part of a ventilated shoetree structure are distinct novelties in this art, and I wish to claim the same herein broadly.

I claim:

1. A ventilated shoetree of the kind described

having a plurality of ventilating slots opening from the toe portion rearwardly, and from the rear portion forwardly, said slots being staggered lengthwise of the forepart and overlapping.

2. A ventilated shoetree of the kind described having a plurality of ventilating slots opening from the toe portion rearwardly, and from the rear portion forwardly, said slots being staggered lengthwise of the forepart and overlapping, thereby affording an automatic widthwise adjustment of the shoetree, both at the toe portion and rear portion widthwise. 10

PAUL S. JONES.
